UNITED STATES PATENT OFFICE.

MANJIRO ONIKI, OF FUKUOKA-KEN, JAPAN.

RICE FOR MANUFACTURING SOY.

1,400,374.

Specification of Letters Patent. Patented Dec. 13, 1921.

Application filed April 18, 1918. Serial No. 229,339.

To all whom it may concern:

Be it known that I, MANJIRO ONIKI, a subject of the Emperor of Japan, and a resident of No. 13 Susakiura-Machi, Fukuoka-5 Ken, Empire of Japan, chemist, have invented a new and useful Improvement in Rice for Manufacturing Soy, of which the following is a specification.

This invention relates to a preparation of 10 rice for use in manufacturing soy by means of a newly discovered micro-organism, and has for its object to produce a special kind of soy having its taste or nutritive or digestive qualities surpassed over the other soy here-15 tofore manufactured.

In order that the invention may be readily understood, I have appended hereunto two sheets of explanatory drawings, which show the magnified view of the aspergillus-onikii, 20 in which—

Figure 1 is a microscopical view of the conidiakeria 1, 2, 3, 4.

Fig. 2 is a like view showing the sterigmas 5, 6, growing upon the head of the conidiakeria.

Fig. 3 is a like view showing the conidiophore fully ripened.

Fig. 4 is a side elevation of an approximately natural sized grains of rice planted 30 with the aspergillus-onikii.

Fig. 5, a, a', b, c, respectively, illustrates different germinating stages of the conidiophore.

Fig. 6 is a longitudinal sectional elevation 35 of the conidiophore, already ripened.

Fig. 7 is a side elevation of the conidiophore, shown on a smaller scale than Fig. 6.

Fig. 8 illustrates over-ripened conidiophore.

Fig. 9, A is a detailed view of the primary sterigma bearing four secondary sterigmas thereon. B is a like view showing the primary and secondary sterigmata assembled.

Fig. 10 is a detailed view of the conidia.

Fig. 11 a, b, c, respectively, illustrates young, enlarged and partly deformed mycelium.

The invention contemplates as an essential base the use of a new species of mycomycetes 50 which is called after my name "aspergillus-onikii". This micro-organism, when cultured upon a suitable culture media germinates in the first place a white, transparent, branched mycelium 11, Fig. 11, a, b, c, re-

spectively, from which, vertically sprouts an 55 aerial hypha or conidiophore in the same manner as other like micro-organisms.

In some instance this aerial hypha which is short and small is found considerably developed to such an extent as to cover the entire surface of the culture media. The colony which is white in the beginning gradually turns to a light yellowish color, then assumes a pure yellow with a slight trace of dark red 60 and finally a brownish yellow.

From the mycelium 11 vertically grows in the form of a branch the conidiophore having a bore 10 comparatively large in diameter, which, when grown but slightly begins like other micro-organisms to develop itself 65 at the top to form a head 13 thereof, the manner in which it develops in the different stages of growth is illustrated in Fig. 5, a, a', b, c, respectively. The stalk 12 of the conidiophore which is straight and vertical and which grows innumerable is more or less tapered toward the head, and fully grown measures 1-1.5 microns long, 10-12 microns wide, 100-550 microns in diameter at the head portion including primary and secondary 70 sterigmas.

The hollow stalk 12 which has no septum throughout the whole length of its bore 10 has the wall 1-2 microns thick, and is coarsely dotted over the outer surface with 75 tiny grains 18, Fig. 5. The stalk 12 proper exhibits brownish yellow at outside while in the interior it is colorless and transparent.

The head proper which is nearly spherical in shape has a clear, distinct boundary of 80 the diameter 50-65 microns and exhibits brownish yellow.

Radially extending and practically covering the entire spherical outer surface of the head 13 are grown innumerable primary and 85 secondary sterigmata 14, 15, respectively, both exhibiting a light yellow color. The primary sterigma 14 which carries at its outer end the secondary sterigma 15 is of the form resembling something like the shape of 90 a club, 18 microns long, 5.2 microns wide.

The secondary sterigma 15 extending outwardly from the outer end of the primary sterigma 14 is of the form resembling something like the shape of a bottle and generally counts four in number as shown in 100 Fig. 9, A.

From the outer end of each of these four

bottlelike secondary sterigmata 14 grows a plurality of egglike conidia 16, one upon the other in successive relation, and extending to form a chainlike connection 8 microns 5 long, 2 microns wide, each being connected by a weak, thin, intermediate septum, as at 18, Fig. 9, B. The egglike conidia, when grown full, transforms itself to assume ball-like formation of the diameter 2 microns 10 long, when an infinitive number of grains make its appearance upon the outer surface thereof, as at 17, Fig. 10.

In germination the thick wall of the conidia develops to a considerable extent and 15 opens up at one or more points to sprout out therefrom colorless, transparent, irregular sized myceliums 11 having neither askus or nucleus at the beginning but soon develop to form at different points several 20 transverse septum 20, Fig. 11.

The present micro-organism naturally exists in the air and elsewhere, and quite frequently it is found deposited upon the outer surface of Katsubushi (flesh of the bonito 25 steamed and dried) during the course of the drying operation in the manufacturing of this particular food of the Japanese, and occasionally it is found in the ear of the person suffering from a certain ear itching 30 disease.

I have found that the present micro-organism is better grown upon a solid media than a liquid culture media, and may be satisfactorily planted upon the rice, bean, bran, 35 bread, or like other artificial media. It grows just as well upon the potato although the growth of the conidia is not so vigorous as other media above enumerated.

Although the growth is slow the rice infusion 40 equally proved to be a good culture media while the bonillon peptone and isinglass proved to the contrary. When planted upon the rice infusion the mycelium growth makes its appearance in the first place from 45 the walls of the vessel containing the liquid which gradually increase until the whole surface of the liquid is covered by a thick layer of corrugated film. The culture upon the straw extract proved unsatisfactory as 50 the fungus growth makes no appearance except on a few points.

I have found also that an artificial liquid media, especially the liquid containing glucose, sucrose and dextrin is very satisfactory 55 as the fungus growth makes its appearance not only upon the liquid surface but at the same time from the walls and bottom of the vessel containing the liquid. The liquid containing galactose, starch paste is also satisfactory 60 while the growth in the solution of lactose and mannitol proved weak and uncertain.

Nitrogen containing media such as Witte's peptone, asparagin, ammonium ni-

trate, ammonium tartarate also invites the 65 growth of the present micro-organism in a most luxuriant manner but has a disadvantage of affecting the nutritive quality of the product.

I have found that the present micro-organism 70 grows best at the temperature of 29-30 degrees C., although it grows at the vicinity of 20 degrees. Other feature of the present micro-organism is that it makes no alcoholic fermentation in rice infusion or in 75 any sugar containing culture media but secretes a considerable quantity of invertase, peptase, etc. The appearance of the hymenium varies according to the nature of the culture media used so that in some instances it is pure yellow while in other instances exhibiting grayish yellow.

Another feature of the present micro-organism is that besides possessing a slightest 80 bitter taste this micro-organism is inherent with a pungent smell somewhat resembling that of the mushroom, and often irritates man's throat when dispersed abundantly in the air.

In carrying out my invention, I prepare 90 in the first place a base or ferment. For this purpose the aspergillus onikii of which I have already described fully is planted upon a preliminarily sterilized suitable medium such as bread, steamed rice, or other 95 appropriate grains, which is then nourished in warm chamber or incubator at a temperature of 27-30 degrees C.

The base thus prepared is then added to by placing it in the mixture of the 6 parts of 100 steamed beans and 4 parts of roasted wheat to the extent that the entire surface of the mixture is eventually flourished with the aspergillus-onikii, care being taken not to be attacked by other bacteria during the 105 course of the operation. The product obtained is termed after my name "Oniki-Koji."

The rice thus obtained is then taken into a vessel containing salt water, left still, and 110 occasionally agitated, until the whole mixture is transformed into the mass of soy when the proteid and starch are decomposed from the bean and wheat into the salt water. Same result can be obtained by placing the 115 Oniki-Koji in a chamber provided with warming means to a temperature approximately 40° C. and agitating it continuously, instead of occasionally, in the same manner as in the mashing process for brewing beer 120 and other liquors.

Then by treating the mass so that the liquid is separated from the residue and subsequently sterilizing and clarifying same makes the product appreciably receivable 125 by the consumer in a sterilized condition and free from contamination and less susceptible to deterioration but without having

its taste or nutritive or digestive qualities impaired.

What I claim is:—

The process of preparing a food composition consisting in culturing aspergillus onikii upon a grain medium, nourishing the same; adding thereto a mixture of steamed beans and roasted wheat; then forming the same into soy, separating the liquid from

the residue, and subsequently sterilizing and 10 clarifying the same.

In testimony whereof I affix my signature in presence of two witnesses.

MANJIRO ONIKI.
